(57) **CLAIM**

I claim the ornamental design for a sport bottle, as shown and described.

DESCRIPTION

FIG. 1 is a left side elevational view of a sport bottle showing my new design, the right side being a mirror image thereof;

FIG. 2 is a rear elevational view thereof;

FIG. 3 is a top plan view thereof;

FIG. 4 is a bottom plan view thereof; and,

FIG. 5 is a front elevational view thereof.

The right side elevational view is the same as the left side elevational view shown in FIG. 1.

1 Claim, 1 Drawing SheetFIG. 1

FIG. 3

FIG. 2

FIG. 5

FIG. 4
